UNITED STATES PATENT OFFICE.

FRANK MOSSBERG, OF ATTLEBORO, MASSACHUSETTS, ASSIGNOR TO MOSSBERG
PRESSED STEEL CORPORATION, OF ATTLEBORO, MASSACHUSETTS, A CORPORA-
TION OF MASSACHUSETTS.

BEAM HEAD.

Application filed April 18, 1922. Serial No. 554,909.

To all whom it may concern:

Be it known that I, FRANK MOSSBERG, a citizen of the United States, residing at Attleboro, in the county of Bristol and State of Massachusetts, have invented certain new and useful Improvements in Beam Heads, of which the following is a specification.

This invention relates to an improvement in the construction of beam heads and the like by which the head is adapted to be adjustably connected to a beam or body on which yarn or other material may be wound; and the object of this invention is to provide a head of this character having a hub member adjustably mounted thereon whereby the hub may be contracted and moved radially bodily to bind the head in adjusted position upon the beam.

A further object of the invention is to provide means whereby the ends of the radiating arms of the hub sections are adjustably attached to the head-plate instead of being permanently or fixedly attached thereto as has heretofore been the case by which construction these radiating arms may be moved radially and so permit a greater range of movement to cause the hub member to better fit and be more effectually clamped about the beam to connect the head thereto. With these and other objects in view, the invention consists of certain novel features of construction, as will be more fully described, and particularly pointed out in the appended claims.

In the accompanying drawings:

Figure 1 is a side elevation illustrating a pair of my improved beam heads adjustably mounted upon a beam.

Figure 2 is a face view of my improved beam-head showing the general arrangement of the different sections of the hub.

Figure 3 is a section on line 3—3 of Figure 2 showing my improved means for detachably securing the middle portion of the hub section to the plate.

Figure 4 is a perspective view showing one of the lugs which is employed in adjustably securing the hub sections, the body portion of which lug is adapted to be welded to the head.

Figure 5 is a perspective view of one of the hub sections detached showing the lug receiving slots therein.

Figure 6 is a section on line 6—6 of Figure 2 showing the elongated slot in the arm

into which the finger portion of the lug is adjustably inserted.

Figure 7 is a detail showing the headed inner end of one of the lugs.

It is found in practice in the construction of beam-heads of this character necessary to so construct the hub portion of the head that it may be contracted to bind the head in adjusted position on the beam, and one practical construction is to form the same in sections having cooperating radiating arms, which arms have heretofore had some portion fixedly attached to the head and by which construction the contracting action of the hub was materially limited. My present improved construction is the provision of means whereby the different sections are mounted to float upon the head and are adapted to be adjusted bodily to contract the hub securely about the beam, and the following is a detailed description of one means by which this result may be accomplished:—

With reference to the drawings, 10 designates the usual body portion of a warp-beam which in this particular case is usually constructed of wood but which, of course, may be made of any suitable material.

In the making of beams of this character the head members 11 are preferably so constructed that they may be adjusted longitudinally along the length of the body portion of the beam in order to regulate its working length.

It is also one of the objects of the invention to construct both the head-plate and the hub sections of sheet metal whereby the whole may be made very light in weight and the hub sufficiently yieldable to be readily contracted to clamp the same upon the body portion and hold the head in any adjusted position thereon.

The periphery of this head-plate is preferably rolled outwardly as at 12, to provide a stiffening flange therefor, and the center of this plate is cut out as at 13 to permit the passage of the end of the beam therethrough.

The hub member 14 is preferably constructed of four separate sections, each having a body portion 16 formed on the arc of a circle with radiating end members 17 all set edgeways against the outer face of the head-plate and at right angles to each other. The radiating end members of each section are spaced apart as at 18 and the end of

- each section is pierced as at 19 to receive the reduced neck portion 20 of the lug 21 to slide thereinto, the outer end of this reduced neck portion being headed over after having been positioned in the slot to prevent the outer ends of these opposite end members from drawing inward toward each other under tension of the binding bolt 24, presently described, the body portion of the lug being 10 then permanently secured, preferably by a spot-welding operation, to the outer face of the head-plate thereby eliminating the usual riveting operation employed for this purpose.
- 15 The body portion of each section is also slotted as at 22, to slidably receive the reduced ends of the lugs 23.

In order to contract these hub members to bind the head in adjusted position on the 20 beam I have provided binding bolts 24 which pass through the adjacent arms 17 of the different hub sections whereby by setting up the nuts on these bolts the different sections are caused to move bodily inwardly 25 to be contracted and so lock the head securely to the beam.

In some instances the head-plate itself is formed in sections in which case I provide 30 guide fingers 25 and 26 and spot weld the different sections to hold the plate sections in alignment or in the same plane with each other.

By my improved construction of beam-head I am enabled to do away with the usual 35 cumbersome cast iron hub which heretofore has been employed for this purpose and have provided one which is much lighter in weight, less expensive to construct, is stronger and more durable and by its use 40 the contractible members of the hub may be permanently secured to the outer face of the head-plate by a welding operation whereby the inner or working face of the head is left plain and smooth, then again by 45 my particular construction the hub sections having radiating arms are set edgeways against the face of the head-plate, the plate is materially stiffened and one of comparatively light weight may be employed, and 50 by the use of my improved head-plate the hub may be readily contracted by a free bodily movement of its sections to grip and bind the body portion of the beam and hold 55 the head in any adjusted position along its length.

The foregoing description is directed solely towards the construction illustrated, but I desire it to be understood that I reserve the privilege of resorting to all the 60 mechanical changes to which the device is susceptible, the invention being defined and limited only by the terms of the appended claims.

I claim:

- 65 1. A beam-head having a separate con-

tractible hub formed of a strip of material set edgeways upon the head plate formed in sections each being mounted to be moved bodily on said head while being contracted and expanded, and means for contracting 70 said sections.

2. A beam-head having a contractible hub formed in sections each section being formed of a strip of material set edgeways upon said head and being adjustably mounted to be moved bodily on said head towards and from the center thereof, and means for drawing 75 said sections toward the center.

3. A beam-head comprising a disc plate, a contractible hub formed in sections and 80 having radiating arms mounted on said plate said arms being connected to said plate to be radially adjusted thereon, and means for contracting said sections.

4. A beam-head comprising a disc plate, a 85 contractible hub formed in sections and having radiating arms mounted on said plate, said arms being adjustably connected to said plate to be moved about bodily thereon, and means for drawing said sections toward each 90 other.

5. A beam-head having a contractible hub member formed in sections each having co-operating radiating arms connected to said head to be moved radially thereon, and 95 means for moving said sections to collectively bind the head in adjusted position on a beam.

6. A beam-head having a contractible hub member formed in sections each having co-operating radially disposed arms, a member 100 fixed to said head and slidably engaging its arm whereby the different hub sections may be adjusted radially, and means for drawing 105 said different sections toward each other.

7. A beam-head having a contractible hub member formed in sections, each having co-operating radially disposed arms each being provided with a slot, a member fixed to said head and having a portion slidably engaging 110 said slot whereby the different hub sections may be adjusted bodily radially, and means for applying pressure to draw said different sections toward each other.

8. A beam-head having a contractible hub member formed in sections, each having co-operating radially disposed arms each being provided with a slot, a member fixed to said head and having a neck portion slidably engaging 115 said slot whereby the different hub sections may be adjusted bodily radially, means for applying pressure to draw said different sections toward each other, and a head on said neck portion to prevent the outer ends of the opposite arms from moving 120 toward each other under tension of said pressure-applying means.

In testimony whereof I affix my signature.

FRANK MOSSBERG.
